[57] CLAIM

The ornamental design for a container, as shown and described.

DESCRIPTION

FIG. 1 is a perspective view, taken from above, of a container showing my new design;

FIG. 2 is an enlarged fragmentary perspective thereof, showing a portion of the rim;

FIG. 3 is a front elevational view thereof, the rear elevational view being identical thereto;

FIG. 4 is a bottom plan view thereof;

FIG. 5 is a side elevational view thereof, the opposite side being identical thereto;

FIG. 6 is a top plan view thereof; and,

FIG. 7 is a cross-sectional view taken along line 7—7 of FIG. 6.
